US0D1026830S

(12) **United States Design Patent** (10) Patent No.: **US D1,026,830 S**
(45) Date of Patent: ** May 14, 2024

(54) **ELECTRICAL BUS BAR**

(71) Applicant: **Delta Electronics (Shanghai) Co., Ltd.**, Shanghai (CN)

(72) Inventors: **Yang Jiang**, Shanghai (CN); **Peiai You**, Shanghai (CN); **Ye Tian**, Shanghai (CN); **Hao Sun**, Shanghai (CN)

(73) Assignee: **DELTA ELECTRONICS (SHANGHAI) CO., LTD.**, Shanghai (CN)

(**) Term: **15 Years**

(21) Appl. No.: **29/816,036**

(22) Filed: **Nov. 18, 2021**

(30) **Foreign Application Priority Data**

(57) **CLAIM**

The ornamental design for an electrical bus bar, as shown and described.

DESCRIPTION

FIG. 1 is a perspective view of an electrical bus bar showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
